UNITED STATES PATENT OFFICE.

JAMES G. DUNGAN, OF LOS ANGELES, CALIFORNIA, ASSIGNOR OF ONE-HALF TO
CHARLES H. COOK, OF MINNEAPOLIS, MINNESOTA.

COOKING-STOVE.

1,158,655.

Specification of Letters Patent.

Patented Nov. 2, 1915.

Application filed January 13, 1915. Serial No. 1,947.

To all whom it may concern:

Be it known that I, JAMES G. DUNGAN, a citizen of the United States, residing at Los Angeles, in the county of Los Angeles and State of California, have invented certain new and useful Improvements in Cooking-Stoves; and I do hereby declare the following to be a full, clear, and exact description of the invention, such as will enable others skilled in the art to which it appertains to make and use the same.

My invention relates to ranges, or other cooking stoves having ovens, and has for its object to improve the construction of the draft passage over the top of the oven, whereby a more even distribution of the heat on the top of the stove and oven are attained.

Generally stated, the invention consists of the novel construction and combination of parts hereinafter described and defined in the claims.

Hitherto, it has been the common practice to provide these stoves, above the oven and immediately under the griddle and top plate of the stove, with flame passages of constant conducting capacity, measured on any line transversely of the stove, or in other words, transversely of the line of draft. With such arrangement, it has been noted that the maximum draft is over the central portion of the top of the oven, or under the central portion of the top of the stove, so that the flames tend to concentrate, producing the greatest heating effect on a line extending centrally from front to rear of the top of the stove. Otherwise stated, the greatest heating effect is at the center and this heating effect diminishes in both directions toward the back and front of the oven. I obviate this defect by constructing the above noted flame passage with a varying cross section having its minimum depth at the central portion of the top of the oven and having an increasing depth in both directions therefrom, to-wit, from the center toward the back and front of the stove or range. This is best accomplished by forming the oven with a top plate that is arched toward its center on straight lines, much after the fashion of a slightly inclined gable roof. This gives a cross section which constantly increases from the center and is thought to be the most desirable form, but, nevertheless, the varying cross section required to offset

the tendency of the draft to concentrate the flames at the center line of the stove, may be accomplished otherwise, than by the above noted preferred arrangement.

In the accompanying drawings which illustrate the invention, like characters indicate like parts throughout the several views.

Referring to the drawings: Figure 1 is a plan view of the stove with some parts sectioned and with the top plate thereof removed; Fig. 2 is a vertical section taken approximately on the line $x^2 x^2$ on Fig. 1, some parts being shown in full; Fig. 3 is a transverse section taken through the stove approximately on the line $x^3 x^3$ on Fig. 1; Fig. 4 is a fragmentary transverse section taken approximately on the line $x^4 x^4$ on Fig. 1; Fig. 5 is an enlarged fragmentary section taken approximately on the line $x^5 x^5$ on Fig. 4; and Fig. 6 is a perspective view showing the arched top plate of the oven removed from the stove.

The cooking stove shown is of the type usually designated as a range, and of the parts thereof, the numeral 1 indicates the base, the numeral 2 the main outer shell, the numeral 3 the oven, the numeral 4 the fire pot, the numeral 5 the grate, the numeral 6 the top plate of the stove, and having the usual griddle 7, and the numeral 8 the smoke pipe, all of which parts, except as herein-after noted, may be of standard or any suitable construction.

The oven 3, instead of having a flat top, as is customary, or a longitudinally arched top, as has hitherto been proposed, is provided with an arched or gabled top 3^a, the ridge of which is spaced from the top of the stove, and extends centrally and longitudinally thereof, so that the varying cross section above indicated is given to the flame passage Y immediately over the top of the oven and under the top of the stove.

The back fire brick lining 9 of the fire pot may be of the usual construction, made either in one or more sections, except that the upper edge portion thereof should follow the outline of the front edge of the top of the oven.

The above described arrangement causes the flames, in passing over the top of the oven, to evenly distribute themselves, and to maintain an even degree of temperature at transverse points on the top of the oven and at all transverse points on the top of the

stove, and from this, it of course follows, that the heat will be equally distributed under the griddles.

What I claim is:

- 5 1. A cooking stove having an oven and a fire pot and provided with a flame passage extended from said fire pot between the top of said oven and the top plate of the stove, and which flame passage, transversely of the line of draft and of the top of the stove, has a varying cross section increasing in both directions from the central line of the draft.
- 10 2. A cooking stove provided with an oven having a gabled top, the ridge of which extends longitudinally under the central portion of the top plate of the stove, thereby
- 15

affording a flame passage that increases in depth transversely of the flame passage.

3. The combination with a cooking stove having a fire pot and an oven, said oven having a transversely arched top affording a flame passage above said oven that increases in depth in both directions from the centering line of draft, of a back lining in said fire pot, which, at its upper edge, follows the line of the arched top of said oven. 20 25

In testimony whereof I affix my signature in presence of two witnesses.

JAMES G. DUNGAN.
